G. W. N. YOST, OF CORRY, PENNSYLVANIA, ASSIGNOR TO CORRY MACHINE COMPANY, OF SAME PLACE.

Letters Patent No. 78,709, dated June 9, 1868.

IMPROVEMENT IN HARVESTERS.

The Schedule referred to in these Letters Patent and making part of the same.

TO ALL WHOM IT MAY CONCERN:

Be it known that I, G. W. N. Yost, of Corry, in the county of Erie, and State of Pennsylvania, have invented a new and improved Narrow-Swath Harvester; and I do hereby declare that the following is a full, clear, and exact description thereof, which will enable others skilled in the art to make and use the same, reference being had to the accompanying drawings, forming part of this specification, in which—

Figure 1 represents a plan or top view of my improved harvester.

Figure 2 is a longitudinal vertical section of the same, taken on the plane of the line $x x$, fig. 1.

Figure 3 is a front elevation of the same.

Similar letters of reference indicate corresponding parts.

The object of this invention is to produce a harvester which can be drawn by one horse, and which can cut as much grain as can be bound by one man, who rides on the platform of the machine. One man for binding, one boy for driving, and one horse, will be all that is required to operate the machine, and the same will therefore be of great advantage to small farmers, and, in fact, on all farms, as, with little power and with insignificant assistance, grain can be reaped by machinery, while, heretofore, much power and much assistance were necessary to keep a reaping-machine in operation. Small farmers were therefore wholly unable to procure or to operate a reaping-machine, and the benefits of the same were consequently only shared by the rich. But, also, on large farms it is often inconvenient to send a large number of men and animals, which might be otherwise more profitably employed, with the harvester, to keep the same in operation.

By the use of my improved reaping-machine all these inconveniences will be overcome, and every farmer will be able to buy and operate it.

The invention consists in the general arrangement of the machine, which consists of a platform resting upon two wheels, and having two shafts for the guidance of one horse. To the front edge of the platform one of the shafts is secured, the other shaft being secured to the curved bar, forming the outer bearing for the axle of the driving-wheel. To the remaining portion of the front edge of the platform is secured a number of fingers, in which the cutter-bar works in the ordinary or any suitable manner.

On the platform is arranged a seat for the binder who binds the grain. To adapt the quantity of grain which is being cut to the faculties of the binder, one of the shoes at the end of the finger-bar is adjustable, so that the width of the swath mowed can be easily adjusted.

A, in the drawing, represents the platform of my improved reaping-machine. The same is made of wood or metal, as may be desired, of suitable shape, wide enough to allow the application of a cutter-bar, B, having the required length to the front edge, alongside of the shafts C C', which project from the edge of the platform and curved bar forming the outer bearing for the axle of the wheel D, as shown in fig. 1. The platform, A, rests upon two wheels D E, one being arranged on each end, as shown. The driving-wheel D, which is behind the shaft C, as shown, is provided with suitable gearing on its body or on its axle, and thereby imparts motion to other gear-wheels a a, which move the pitman b. The latter imparts the ordinary reciprocating motion to the cutter-bar B. The said cutter-bar is held and guided in fingers F F', which are fastened to the platform A, as shown.

G G' are two shoes projecting from the platform, one at either end of the cutter-bar, so as to take in all the grain which stands in the required space. One of these shoes is removable, and can be adjusted on the platform so as to make the swath cut wider or narrower as may be desired. In fig. 1, the shoe G, which is nearest to the shafts C, is represented as having been adjusted, so as to be in place of the outer finger F', whereby a narrower swath is produced. If a wider swath would have to be cut, the shoe G would exchange places with the finger F'.

The grain cut by the bar B is, by a suitable reel or otherwise, deposited upon the platform A, where it is at once bound into bundles of the required size.

To facilitate the binding, a seat, H, has been arranged upon the platform for the binder to sit on, and a cushion, I, for him to kneel on may also be arranged on the platform, as shown.

Two bent plates J J may also be arranged for the convenience of the binder upon the platform A, for the purpose of enabling the binder to raise the grain above the platform, to allow the string to be passed easily around it.

Having described my invention, what I claim as new, and desire to secure by Letters Patent, is—
The movable adjustable shoe G, when arranged substantially as described, so as to adjust the width of the swath to the capacity of the binder, as set forth.

G. W. N. YOST.
